ATTORNEYS

UNITED STATES PATENT OFFICE.

HAROLD ASHWORTH AND ALBERT D. WELCH, OF KENNEBUNKPORT, MAINE.

DESIGN FOR A JUNCTION-BOX.

No. 39,911.

Specification for Design.

Patented April 6, 1909.

Application filed November 12, 1908. Serial No. 462,352. Term of Patent 7 years.

To all whom it may concern:

Be it known that we, HAROLD ASHWORTH and ALBERT D. WELCH, citizens of the United States, residing at Kennebunkport, in the county of York and State of Maine, have invented a new, original, and ornamental Design for a Junction-Box, of which the following is a specification, reference being had to the accompanying drawings, forming a part thereof.

Figure 1 is a side elevation of a junction

box showing my new design; and Fig. 2 is a plan view thereof.

We claim:

The ornamental design for a junction box as shown.

HAROLD ASHWORTH.
ALBERT D. WELCH.
